(57) CLAIM

The ornamental design for a beverage maker as shown and described.

DESCRIPTION

FIG. 1 is a front perspective view of a first embodiment of a beverage maker showing our design;

FIG. 2 is a side view thereof;

FIG. 3 is an opposite side view thereof;

FIG. 4 is a front view thereof;

FIG. 5 is a rear view thereof;

FIG. 6 is a top view thereof; and,

FIG. 7 is a bottom view thereof.

In the drawings, the broken lines depict portions of the article that form no part of the claimed design.
